UNITED STATES PATENT OFFICE.

OSCAR GREENBAUM, OF PHILADELPHIA, PENNSYLVANIA, ASSIGNOR TO LANGFELD BROS. & CO., OF PHILADELPHIA, PENNSYLVANIA, A FIRM COMPRISED OF ABRAHAM M. LANGFELD AND MORRIS F. LANGFELD.

BAG AND BAG-FRAME THEREFOR.

1,114,607.

Specification of Letters Patent. Patented Oct. 20, 1914.

Application filed October 4, 1913. Serial No. 793,340.

To all whom it may concern:

Be it known that I, OSCAR GREENBAUM, a citizen of the United States, residing at Philadelphia, in the county of Philadelphia and State of Pennsylvania, have invented 5 certain new and useful Improvements in Bags and Bag-Frames Therefor; and I do hereby declare the following to be a full, clear, and exact description of the invention, such as will enable others skilled in 10 the art to which it appertains to make and use the same, reference being had to the accompanying drawings, and to characters of reference marked thereon, which form a 15 part of this specification.

This invention has reference, generally to improvements in that class of bag-frames which are employed more especially in connection with ladies' hand bags, chatelaine bags, and the like; and the present invention has for its principal object to provide a neat and simply constructed bag frame, in which the side or leg-members of the hinged or pivotally connected frame-sections are 20 made with slotted or cut-away parts, near the corners of the two frame-sections, thereby allowing for a full complement of the mouth-portion of the bag-body attached to the frame-sections, and also providing for a 25 full expanse of the bag-body, the marginal side-portions of the bag-body extending to the outer edges of the side or leg-members of the frame-sections, so as to entirely cover the same, and at the same time entirely doing 30 away with the usual wrinkled and unsightly upper corners of the bag-body attached to the frame-sections.

Other objects of the present invention not at this time more particularly enumerated 40 will be clearly understood from the following detailed description of the present invention.

With the various objects of the present invention in view, the invention consists, 45 primarily, in the novel bag-frame herein-after more particularly set forth; and, the invention consists, furthermore, in the novel arrangement and combination of the bag-frame and the bag-body attached thereto, 50 whereby the results hereinabove mentioned are obtained, all of which will be described in detail in the following specification, and then finally embodied in the clauses of the claims which are appended to and which 55 form an essential part of said specification.

The invention is clearly illustrated in the accompanying drawings, in which:—

Figure 1 is a front face view of a hand-bag and a frame-section to which the bag-body is attached according to the principles 60 of the present invention; and Fig. 2 is a front view of the bag-frame, with the bag-body omitted from said view. Fig. 3 is an end view of the bag-frame and bag-body attached thereto, the hinged or pivoted 65 frame-sections and the bag-body being represented in their opened relation; and Fig. 4 is a vertical sectional representation, on an enlarged scale, said section being taken on line 4—4 in Fig. 2, looking in the direction 70 of the arrow α .

Similar characters of reference are employed in the said above described views, to indicate corresponding parts.

Referring now to the said drawings, the 75 reference-character 1 indicates a complete hand-bag made of leather, or other suitable material, the reference-character 2 indicating the front and back face-portions of the bag-body, suitably sewed or otherwise secured at their marginal edge-portions 3 to the end-pieces or gussets 4.

The bag-frame proper consists of a pair of metal frame-sections 5, each frame-section comprising an upper or top member 6, extending horizontally, and a pair of side or leg-members 7, extending in downward directions from the respective end-portions or angles 8, as shown in Fig. 2 of the drawings.

The respective side or leg-members of the 90 two frame-sections 5 are pivotally connected in any usual manner, as at 9, and the upper or top-members 6 of said frame-sections are provided with any suitably constructed locking means for retaining the frame-sections 95 in their closed relation, the locking means here shown being in the form of retaining or holding knobs, as 10. One of the frame-sections is also provided with the usual fixtures 11 for the attachment thereto of a suitable hand-strap 12, in the manner represented in Figs. 1 and 3 of the drawings. The side or leg-members 7, as well as the upper or top-member 6 of each frame-section 5, are made of sheet metal which is suitably doubled upon itself so as to form frame-portions which are U-shaped in cross-section and to thereby provide the usual chambered portions 13 in which the edge-portions 14 which surround the mouth of the 100 105 110

bag-body, as well as the edge-portions 15 of the respective gussets are respectively arranged and permanently secured in any usual manner.

- 5 Referring now to Figs. 2 and 4 of the drawings, it will be seen, that the said side or leg-members 7 of each frame-section 5 are provided in their upper portions, near the corners or angles 8 of the bag frame, 10 with slots or cut-away parts, as 16, bound by the straight marginal edge-portions 17 and 18, and the convexly curved portion 19. When the edge-portions 14 of the bag-body have been secured in the chambered 15 parts of the upper or top-members 6, and the edge-portions 15 of the gussets have been similarly secured in the chambered portions of the side or leg-members 7, the parts 20 of the bag-body, where they are secured to 20 the gussets, are arranged in and extend from the said slots or cut-away parts 16 with which the side or leg-members 7 are provided. This arrangement of these various parts allows of the flat arrangement and 25 connection of the upper portions of the bag-body to the two frame-sections of the bag-frame, as represented in Fig. 1, thus obtaining the full complement of the mouth-portion of the bag-body and at the same 30 time entirely over coming the usual wrinkled and unsightly condition of the upper corners of the bag-body; and, furthermore, the possible tearing out of the bag-body at the corners of the bag-frame and from the upper 35 or top-member of the frame-sections is entirely avoided. It will also be evident, that by this means the side or leg-members of the frame-sections are hidden from view, so that thereby a neat and handsome 40 construction of bag is the result.

I claim—

1. A bag-frame consisting of hinged frame-sections, each frame-section comprising an upper or top-member and a pair of side or leg-members, said side or leg-members being formed with slots or cut-away portions, combined with the bag-body and gussets of a bag, said bag-body and gussets being respectively attached to the upper or 45 top-members and to the side or leg-members of the frame-sections, and the upper corner-portions of the bag-body being arranged in said slots or cut-away parts and extending outwardly therefrom, substantially as and for the purposes set forth.

2. A bag-frame consisting of hinged frame-sections, each frame-section comprising an upper or top-member and a pair of side or leg-members, said side or leg-members being formed with slots or cut-away portions, said slots or cut-away portions being bounded by straight edge-portions and

a convexly curved edge-portion, combined with the bag-body and gussets of a bag, said bag-body and gussets being respectively attached to the upper or top-members and to the side or leg-members of the frame-sections, and the upper corner-portions of the bag-body being arranged in said slots or cut-away parts and extending outwardly therefrom, substantially as and for the purposes set forth.

3. A bag-frame consisting of hinged frame-sections, each frame-section comprising an upper or top-member and a pair of side or leg-members, said upper or top-member and said side or leg-members having sides forming U-shaped chambers, and each side or leg-member being formed in one of its said sides with slots or cut-away portions, combined with the bag-body and gussets of a bag, said bag-body having its marginal edges surrounding its mouth arranged and secured in the U-shaped chambers of said upper or top-members, the gussets having marginal edge-portions arranged and secured in the U-shaped chambers of said side or leg-members, and the upper corner-portions of the bag-body being arranged in the slots or cut-away parts of 80 said side or leg-members and extending outwardly therefrom, substantially as and for the purposes set forth.

4. A bag-frame consisting of hinged frame-sections, each frame-section comprising an upper or top-member and a pair of side or leg-members, said upper or top-member and said side or leg-members having sides forming U-shaped chambers, and each side or leg-member being formed in one of its said sides with slots or cut-away portions, said slots or cut-away portions being bounded by straight edge-portions and a convexly curved edge-portion, combined with the bag-body and gussets of a bag, said bag-body having its marginal edges surrounding its mouth arranged and secured in the U-shaped chambers of said upper or top-members, the gussets having marginal edge-portions arranged and secured in the U-shaped chambers of said side or leg-members, and the upper corner-portions of the bag-body being arranged in the slots or cut-away parts of said side or leg-members and extending outwardly therefrom, substantially as and for the purposes set forth.

In testimony, that I claim the invention set forth above I have hereunto set my hand this first day of October, 1913.

OSCAR GREENBAUM.
